J. S. THOMPSON

BRAKE SHOE MOLD

Filed July 20, 1923

Fig. 1

Fig. 2.

Inventor:
James S. Thompson
By: Wm. O. Bell
City:

UNITED STATES PATENT OFFICE.

JAMES S. THOMPSON, OF PELHAM, NEW YORK.

BRAKE-SHOE MOLD.

Application filed July 20, 1923. Serial No. 652,781.

To all whom it may concern:

Be it known that I, JAMES S. THOMPSON, a citizen of the United States, residing at Pelham, in the county of Westchester and 5 State of New York, have invented certain new and useful Improvements in Brake-Shoe Molds, of which the following is a specification.

This invention relates to the manufacture 10 of brake shoes and its primary object is to simplify and facilitate setting up the mold for casting operation and opening the mold to remove the brake shoe casting.

A further object of the invention is to 15 provide a permanent mold of simple and improved construction in which the parts to be embedded in the casting can be easily inserted and the mold closed for the casting operation, and which will permit the shoe casting to be easily removed when the mold is open.

And a further object of the invention is to 20 construct a metal mold with a brake shoe cavity faced with refractory material so that the parts to be embedded in the shoe can be easily inserted in the mold cavity without damaging the refractory facing and so that the shoe casting may be easily removed from the mold without damaging the refractory facing.

Referring to the drawing illustrating a 25 selected embodiment of the invention—

Fig. 1 is a transverse sectional view on the line 1—1 of Fig. 2.

Fig. 2 is a longitudinal view on the line 30 2—2 of Fig. 1.

Referring to the drawings, the mold comprises a metal drag 5 and a metal cope 6 having a mold cavity 7 and a pouring gate 40 8. The cope has an enlarged opening 9 to receive a sand plug 10 which is preferably held in a holder 11 fitting snugly in the opening 9. This sand plug is formed with a recess 12 constituting a part of the mold cavity 7 and adapted to receive the attaching lug 13 and the baked sand core 14 to form the opening in the lug. A reinforcing back 15 is held in place snugly against the top of the mold cavity by wires 16,

50 which are engaged with a cross-bar 17 resting on the top of the plug and which extend down through the plug and have their ends twisted together at 18 beneath the back. Thus the wires suspend the back in

its proper position in the mold cavity, and 55 the back supports the lug 13 and the core 14 thereon in the recess of the plug.

The mold cavity 7 is faced with refractory material forming the walls thereof, and this refractory material abuts against 60 the plug so that all the walls of the mold cavity are refractory.

The parting line between the drag and the cope is formed by succession of steps transversely of the mold so that the side 65 wall 19, the bottom wall 20 and the end wall 21 of the mold cavity are located on the drag, whereas the top wall 22, the side wall 23 and the end wall 24 of the mold cavity are located on the cope. The walls of the 70 recess 12 are, of course, located on the cope. The drag and the cope are also divided by the parting lines 25, 25', which form a continuation of the parting line extending through the mold cavity walls. This construction provides for the cope being lifted 75 from the drag or the drag being lowered from the cope to open the mold for the removal of the finished shoe casting without damaging the refractory facing.

To secure the mold, the drag and the cope 80 together I provide a yoke 26 which is pivoted at 27 on one member and is provided with a set screw 28 whereby it may be clamped in place when swung to closed position, as shown in the drawing.

My invention provides a permanent mold of comparatively simple construction, in which the drag and the cope are constructed to interfit so that they can be supported to permit convenient removal of the shoe casting and to permit the insertion of the reinforcing back, the lug and its core in the mold cavity for another casting.

My invention can be employed for making castings other than brake shoes and I consider myself entitled to make all such changes in the form, construction and arrangement of parts as may be necessary or desirable for this purpose, and for making 95 100 different kinds, shapes and sizes of brake shoes, which fairly fall within the scope of the following claims.

I claim:

1. A permanent mold for making castings comprising a metal drag and a metal cope having a mold cavity therein, the bottom wall, one side wall and one end wall of

the mold cavity being formed on the drag, and the top wall, one side wall and one end wall being formed on the cope.

2. A permanent mold for making castings comprising a metal drag and a metal cope having a mold cavity therein, the bottom wall, one side wall and one end wall of the mold cavity being formed on the drag, the top wall, one side wall and one end wall of the mold cavity being formed on the cope, and all of said walls being faced with refractory material.

3. A permanent mold for making castings comprising a metal drag and a metal cope having a mold cavity therein, said mold cavity having its walls faced with refractory material, and the parting line between the drag and the cope extending downward from the top of the mold in steps through the mold cavity to the bottom of the mold.

4. A permanent mold for making castings comprising a metal drag and a metal cope having a mold cavity therein, a refractory facing for the walls of said cavity, the

parting line between the drag and the cope extending down from the top of the mold to a step at the top of one side wall and one end wall of the mold cavity and thence down to the bottom of the other side wall and the other end wall and through the bottom of the mold.

5. A mold for casting a brake shoe, comprising a metal drag and a metal cope having a mold cavity therein, the walls of said mold cavity being faced with refractory material, said cope having an opening therein, a sand plug seated in said opening and having a recess forming a part of the mold cavity, means seated in the plug for suspending the back in the mold cavity and the attaching lug and the core for forming the opening therein in the recess in the plug, the bottom, one side wall and one end wall of the mold cavity being formed in the drag, the top, one side wall and one end wall of the mold cavity being formed in the cope, and means for securing the drag and cope together.

JAMES S. THOMPSON.
